Primary Examiner — Elizabeth J Oswecki(74) Attorney, Agent, or Firm — Pauley Erickson & Kottis(57) CLAIM

The ornamental design for a shoe, as shown and described.

DESCRIPTION

FIG. 1 is a side view of a shoe, showing my new design;

FIG. 2 is an opposite side view thereof;

FIG. 3 is a top plan view thereof;

FIG. 4 is a bottom plan view thereof;

FIG. 5 is a rear perspective view thereof;

FIG. 6 is a front elevation view thereof;

FIG. 7 is a front perspective view thereof; and,

FIG. 8 is a rear elevation view thereof.

The broken lines shown in the drawings represent portions of the shoe that form no part of the claimed design.

1 Claim, 4 Drawing Sheets(56)
